UNITED STATES PATENT OFFICE.

ALFRED C. EASTMAN, OF AUGUSTA, MAINE.

LAP-SEAM GAGE.

1,325,629.

Specification of Letters Patent. Patented Dec. 23, 1919.

Application filed May 6, 1918. Serial No. 232,930.

To all whom it may concern:

Be it known that I, ALFRED C. EASTMAN, a citizen of the United States, residing at Augusta, in the county of Kennebec and State of Maine, have invented certain new and useful Improvements in Lap-Seam Gages, of which the following is a specification.

This invention relates to certain improvements in lap seam gages and has relation more particularly to a device of this general character especially designed and adapted for use in the manufacture of shoes or other similar structures and it is an object of the invention to provide a device of this general character having novel and improved means whereby guiding elements coact with the free marginal portions of the overlapping pieces of material whereby a line of stitching connecting said overlapping portions of the pieces of material is arranged in predetermined proximity to the free margin of the overlapping portion of one of the pieces of material.

The invention also has for an object to provide a novel and improved gage whereby the extent of overlapping of the pieces of material is regulated without the exercise of any particular skill upon the part of the operator.

Another object of the invention is to provide a novel and improved gage of this general character especially adapted for use in the formation of the lap seam connecting the vamp and tongue of a shoe or other similar structure and whereby a seam is produced which prevents the rolling of the vamp in the completed shoe when the wearer inserts his foot within the shoe.

Furthermore, it is an object of the invention to provide a novel and improved gage which is movably supported upon the top or work plate of a sewing machine whereby the same may be readily thrown into or out of working position relative to the sewing needle together with coacting means carried by the gage and the top or work plate of the sewing machine for holding the gage in working position.

A still further object of the invention is to provide a novel and improved gage of this general character which is provided with guide elements coacting with the free edges of the overlapping portions of the pieces of material together with means car-

ried by the gage adapted to coact with the overlapping margin of the under piece of material to hold said piece of material immediately adjacent the gage from rising and riding over the gage which would otherwise materially handicap and interfere with the sewing operation.

The invention consists in the details of construction and in the combination and arrangement of the several parts of my improved lap seam gage whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a fragmentary view in top plan of the top or work plate of a sewing machine showing a gage constructed in accordance with an embodiment of my invention applied thereto and in working position, the coacting work being indicated in fragment;

Fig. 2 is a view in side elevation of my improved gage with a portion in section, the top or work plate of the sewing machine being diagrammatically indicated by a dotted line; and

Fig. 3 is a view in bottom plan of my improved gage with certain of the parts omitted.

As disclosed in the accompanying drawings P denotes the top or work plate of a sewing machine or stitcher and 1 denotes a needle aperture or opening, and 2 denotes a feed dog or plate, said opening 1 and dog or plate 2 being indicated by dotted lines.

Overlying the working face of the plate P is my improved gage G. The gage comprises an elongated flat strip or body 3 possessing a certain degree of inherent resiliency and having its rear end or tail portion 4 upwardly disposed to afford a convenient means whereby the gage may be readily adjusted into or out of working position. The forward end of the strip or body 3 is disposed on a predetermined incline as indicated at 5 and the forward or high point of said inclined edge 5 is provided with the

forwardly and longitudinally directed extension or lip 6 which, when the gage is in working position, terminates in close proximity to the needle aperture or opening 1 5 and substantially in perpendicular relation to the plane occupied by said aperture or opening extending transversely of the plate P.

Inwardly of the beveled end 5 or in close 10 proximity thereto, the strip or body 3 is provided with an opening 7 in which is mounted a bushing 8. Disposed through the bushing 8 is a headed member 9 in threaded engagement with the top or work plate P 15 and which serves as a pivot for the strip or body 3 so that said strip or body 3 may readily be swung into or out of working position in accordance with the occasions of practice. As is particularly illustrated 20 in Fig. 2 the portion of the shank of the headed member 9 arranged within the bushing 8 has its periphery smooth and unobstructed so that the desired swinging movement of the strip or body 3 may be effected 25 with a minimum of frictional resistance. The lip or extension 6 hereinbefore referred to in the present embodiment serves as a vamp guide and secured to the under surface of the strip or body 3 and underlying 30 the extension or lip 6 and the adjacent portion of the strip or body 3 is a supplemental plate 10 which rests upon the top or work plate P and serves to provide the lip or extension 6 with the requisite thickness so 35 that the proper coaction of said lip or extension 6 as a gage with the vamp V or other piece of material is assured. The under surface of the strip or body 3 adjacent the inner or low portion of the beveled end 5 has also 40 secured thereto a second plate 11 of a thickness equal to the thickness of the supplemental plate 10 and which plate also contacts with the top or work plate P. The plate 11 has been found desirable in order 45 to prevent any twisting or distorting of the forward or working end portion of the strip or body 3.

Secured to the top face of the strip or body 3 adjacent the lip of extension 6 is a 50 plate 12 provided with the forwardly directed extension or finger 14 terminating in advance of the extension or lip 6 and which is adapted to overlie the marginal portion of the vamp V or other piece of material 55 when the gage is in working position, and the extension or finger 14 serves to hold the vamp or other piece of material in applied position, and thereby prevents said vamp or the like from riding over the extension 60 or lip 6 during a working operation. In practice it has been fully established that the extension or finger is of great importance in the successful use of my improved 65 gage.

65 Extending longitudinally from the work-

ing end of the strip or body 3 is an elongated arm 15 having its outer end portion provided with an upstanding flange 16 arcuate in plan with the bow inwardly directed. The flange 16 in the present embodiment of 70 my invention serves as a tongue guide or a guide for the second or upper piece of material arranged above the piece of material with which the guide 6 coacts.

The arm 15 or more particularly the guide 75 16 carried thereby serves to regulate the degree or extent of overlapping between the vamp V and the tongue T or other piece of material and in order that this degree or extent of overlapping may be regulated in 80 accordance with the requirements of practice, I find it of advantage to have the arm 15 supported by the strip or body 3 for longitudinal adjustment. As herein disclosed the portion of the arm 15 overlying 85 the strip or body 3 is provided with the longitudinally disposed slot 17 through which are directed the clamping screws 18 in threaded engagement with the strip or body 3. By this arrangement it will be at 90 once self-evident that the arm 15 may be adjusted longitudinally as the occasions may require and will be effectively maintained in its different positions by the clamping screws or members 18. It will also be self-evident that the relative positions of the extension or lip 6 and the flange 16 will determine the degree or extent of overlapping of the pieces of material, such as the vamp V and the tongue T, which are adapted to 100 be united. I also find it of advantage to interpose between the top or work plate P and the strip or body 3 at the pivotal mounting of said strip or body the spacing washer or plate 19. The headed member 9 is disposed through the plate or washer 19 as particularly illustrated in Fig. 2, whereby said plate or washer 19 is maintained in its desired position.

The rear portion of the strip or body 3 110 adjacent the tail 4 is provided with an opening 20 through which is adapted to extend the upstanding pin 21 carried by the top or work plate P and which pin is so positioned as to hold the gage in its working position. 115 It is to be understood that the inherent resiliency of the strip or body 3 readily permits the same to be engaged with or disengaged from the pin 21.

My improved lap seam gage as herein 120 disclosed is particularly adapted for use in connection with vamps and tongues of shoes and in practice the lip or extension 6 contacts with the edge of the vamp and the flange 16 with the edge of the overlapping 125 portion of the tongue T. The position of the working end of the extension or lip 6 relative to the needle aperture or opening 1, when the gage is in working position, determines the distance from the edge of the 130

vamp to the stitching. As before explained the flange or guide 16 controls the degree or extent to which the vamp V and the tongue T will overlap. After the first row 5 of stitching has been run across the tongue or the edge of the vamp, the gage is swung out of working position.

From the foregoing description, it is thought to be obvious that a lap seam gage 10 constructed in accordance with my invention is particularly well adapted for use by reason of the convenience and facility with which it may be assembled and operated and it will also be obvious that my invention is 15 susceptible of some change and modification without departing from the principles and spirit thereof and for this reason I do not wish to be understood as limiting myself to the precise arrangement and formation of 20 the several parts herein shown in carrying out my invention in practice except as hereinafter claimed.

I claim:

A lap seam gage comprising a body adapted to be supported by the working plate of 25 a sewing machine and movable relative to the needle opening, the working end of the body being inclined transversely, the high point of said inclined end serving as a guide adapted to contact with an edge of a piece 30 of material to position said material relative to the needle opening, a second guide member secured to the body adjacent the low point of the inclined working end and terminating in advance of said working end, 35 said second guide member contacting with the lapping edge of a second piece of material, and a forwardly directed finger carried by the high portion of the working end of the body and adapted to overlie the piece of 40 material with which the first named guide coacts.

In testimony whereof I affix my signature.

ALFRED C. EASTMAN.
